UNITED STATES PATENT OFFICE.

SAMUEL S. SIMRAK, OF SAN FRANCISCO, CALIFORNIA, ASSIGNOR TO ALBERT R. HERMAN, OF SAME PLACE.

GAS-ENGINE.

SPECIFICATION forming part of Letters Patent No. 598,025, dated January 25, 1898.

Application filed June 22, 1896. Serial No. 596,505. (No model.)

To all whom it may concern:

Be it known that I, SAMUEL S. SIMRAK, a citizen of the United States, residing at San Francisco, in the county of San Francisco and State of California, have invented certain new and useful Improvements in Gas-Engines; and I do hereby declare the following to be a full, clear, and exact description of the invention, such as will enable others skilled in the art to which it appertains to make and use the same.

My invention relates to improvements in explosive gas or gasoline engines.

The invention consists of certain novel constructions, combinations, and arrangements of parts, all of which will be hereinafter more particularly set forth and claimed.

In the accompanying drawings, forming part of this specification, Figure 1 represents a perspective view of the engine embodying my invention. Fig. 2 represents an enlarged detail side elevation of the upper portion of the same. Fig. 3 represents a top plan view of said engine. Fig. 4 represents a detail central vertical section through the combustion-chamber. Fig. 5 represents a horizontal section through the same; and Fig. 6 represents a detail side elevation of the upper portion of the engine, taken on a line at right angles to that shown in Fig. 2.

A in the drawings represents the frame of the engine, which supports the main shaft R, belt-wheel X, vertical shaft F, and cylinder B.

C is the combustion-chamber, attached to the upper end of the cylinder B in any suitable manner and containing the admission and exhaust valves C' and C², respectively, and the electric igniting device, which will be hereinafter more fully described.

D is the cap for the combustion-chamber C. It is made hollow, as shown in Fig. 3, so that the heat to which it is subjected when the engine is running will be imparted to the air which is drawn through it from the external atmosphere to form a part of the explosive mixture, as will be hereinafter more fully explained. This cap is held in position on the combustion-chamber by suitable bolts and is provided with a removable plug T, which when removed leaves that portion of the combustion-chamber occupied by the

sparking electrodes exposed to view. The passage formed in the said cap D communicates at one end with the atmosphere without by means of an opening Q and at its opposite end with a pipe J, that is connected with the inlet to the combustion-chamber through a passage c' and with the source of supply by a pipe W, governed by a valve M, having a pendent stem m. The valve C' is seated over the discharge-port of this passage c' and is provided with a pendent stem V. This stem in turn is provided with an adjustable laterally-extending arm K, by means of which the valve M is lifted off its seat to admit the combined supply of liquid hydrocarbon and air into the combustion-chamber. The arm K is adapted to normally engage the lower end of the rod m and raise the valve M simultaneously with the valve C', so that the fresh supply of hydrocarbon for the combustion-chamber will have free passage to the same. This simultaneous action of valves C' and M only takes place when the engine is running normal. When the action becomes too rapid, the rod K is moved horizontally to one side out of the same vertical plane with the rod m, so as not to engage and operate the latter by the forked end g' of a pivoted double bell-crank lever G. The lower arm g² of this lever is pivoted at H to the frame, and the horizontal arm g³ is engaged at its outer end g by a flanged sleeve S, loosely mounted on the shaft F and raised by the action of the ball-governor, mounted below the same. A spring g⁴ is secured at one end to the arm g³ and at the other to a rod g⁵, rigid on the pivot-rod H. The said shaft F is journaled in suitable boxes upon the frame and is so geared to the shaft R as to revolve once to every two revolutions of the latter.

It will be observed from the above that should the engine reach an abnormal speed the governor would raise the sleeve S, which would operate the lever G to move the rod K out of alignment with the stem m, so that upon the upward movement of the said rod the valve M would not be operated, and thus the cylinder would receive no charge and the engine would regain its normal speed.

The outlet-valve C² covers the port of an exhaust-passage c² and is provided with a pendent stem V'. The valves C' C² are al-

ternately raised off their seats by a lever *L*, pivoted to the cylinder at *y*, so that its free ends are adapted to alternately engage the stems *V* and *V'*, respectively, and raise the same as said lever is rocked upon its pivot. This rocking is caused by a roller *l*, mounted on one arm of said lever and engaging a cam-groove *p'*, formed by oppositely-facing cams *P P'*, rigidly mounted upon the shaft *F*.

10 The sparking in the combustion-chamber *C* for exploding the liquid hydrocarbon is produced by electrodes *d p*, respectively. The electrode *d* is cylindrical in form and is mounted in an insulating-sleeve *m'* in a cap *e*, secured in the wall of the chamber *C* by means of a thumb-nut *t*, which holds it firmly in position. Said electrode is provided upon its external end with a hand-wheel *a*, by means of which it can be revolved when the thumb-nut *t* is loosened. This electrode is connected in an electric circuit by a suitable wire secured to it outside of the cylinder. The oscillating electrode *p* is provided upon its inner end with a contact-point *n* and is mounted 25 upon a vertical shaft *b*, which passes upward and out of the cap *e*. A spring-lever *c* is rigidly secured to the protruding end of the shaft *b* by a clamping-block *b'*. This lever is adapted to be engaged at its free end by a cam *f*, mounted on shaft *F*, whereby said lever is oscillated with a snapping action to move the electrode with a similar action and cause it to make and rapidly break contact with the electrode *d* with the resulting spark. The electrode *p* is held normally out of contact with the electrode *d* by a spring *h*, secured to the block *b'* and bearing with its free end upon the side of the chamber *C*.

The piece *d*, as before described, is insulated from all other parts by the insulating material *m'* and is connected to one wire leading from an electric circuit, while the other wire from the circuit is connected to the shaft *b*. In order that the spark may be formed 45 with certainty, it is necessary that the contacting surfaces of the electrodes *p* and *d* be kept clean. To effect this, the piece *d* is so constructed that by loosening the binding-nut *t* and turning the thumb-wheel *a* the cylindrical electrode *d* can be revolved within the insulator, and while such revolution is in progress the contact-piece *n* is caused to rub on the piece *d* by pressing on the spring-lever *c*. This abrasion or rubbing of the electrode-surfaces effectually cleans them. This operation may be performed readily at any time before the engine is started and the certain 55 operation of the sparking mechanism thus assured.

60 The lever *L* is so constructed that its ends *E* and *O* are not always in contact with the stems *V* and *V'* of the valves, and there is a certain period of time during the cycle of operations when the lever *L* remains without 65 motion, as when the charge is being compressed, ignited, and expanded. The construction is such that when the free ends *E*

and *O* do come into contact with the stems of the valves it will be with a rapid motion, so that the valves may be opened or closed quickly.

Experience has shown that gasoline or other hydrocarbon may be used in a motor of proper design without the necessity of first producing a gas or vapor.

75 By the use of my improved construction and arrangement it is not necessary to employ a carburetor, but the engine as herein constructed can be operated by the introduction of the hydrocarbon in liquid form in 80 quantity that is automatically regulated by the power developed.

If it is desired to employ illuminating or other gas in place of hydrocarbon, it is only necessary to provide an admission-valve of 85 larger area.

This engine is single-acting, and its crank-shaft makes two revolutions to one revolution of the shaft operating the valve mechanism. The forward motion of the piston is caused 90 by the explosion of the inclosed mixture. On the upward stroke of the piston the products of combustion are expelled, and on the following downstroke a fresh supply of the explosive mixture is drawn into the cylinder 95 and then compressed on the upward motion of the piston and ignited when the piston has regained its uppermost position.

Having now described my invention, what I claim as new, and desire to secure by Letters 100 Patent, is—

1. In an explosive gas or gasoline engine, the combination with a cylinder and piston, of valves arranged on diametrically opposite sides of the cylinder, covering respectively 105 an inlet and an exhaust from said cylinder, a semicircular rocking lever, pivotally mounted upon the side of the cylinder, the ends being adapted to extend around the cylinder and beneath the valves whereby they may be raised alternately, and a cam directly connecting said lever with a moving part of the engine, substantially as described.

2. In an explosive gas or gasoline engine, the combination with a cylinder, and piston, 115 of valves arranged on diametrically opposite sides of the cylinder, covering respectively an inlet and an exhaust of said cylinder, a pivoted lever adapted to extend half-way around the cylinder and having a rocking movement longitudinally of said cylinder, its ends extending under the valves for alternately lifting them, and a closed cam connected to the moving parts of the engine, and directly engaging the rocking lever between 120 one end and its pivoted point for positively oscillating the same, substantially as described.

3. In an explosive gas or gasoline engine, the combination with a cylinder and piston, 130 of valves covering respectively an inlet and an exhaust from said cylinder, a rocking lever for operating said valves, an auxiliary inlet-valve adapted to be operated by a pro-

jection or arm on the main inlet-valve, a bell-crank lever provided with a guiding end directly engaging said arm for moving it out of the position for engagement with said auxiliary valve, and a governor for operating said bell-crank lever when the engine reaches an abnormal speed so that the auxiliary valve will not be opened to supply the cylinder until the engine has regained its normal speed, substantially as described.

4. In an explosive gas or gasoline engine, the combination with a cylinder and piston, of inlet and exhaust valves for said cylinder, an auxiliary inlet-valve, a lever for operating all of said valves, an independent pivoted bell-crank lever for throwing said means out of operative position as far as the auxiliary valve is concerned and a governor for operating said bell-crank lever, substantially as described.

5. In an explosive gas or gasoline engine, the combination with a cylinder and combustion-chamber, of a removable hollow cap adapted to close the upper end of said combustion-chamber, the hollow portion being open directly to the atmosphere at one end and connected with the combustion-chamber at the other by means of a pipe, provided with a hydrocarbon-inlet and through which the external air for the explosive mixture is drawn into the combustion-chamber and thereby heated before coming into contact with the hydrocarbon, substantially as described.

6. In an explosive gas or gasoline engine, the combination with a cylinder and a combustion-chamber, of an electric igniting device comprising a stationary electrode and an oscillating electrode, the said oscillating electrode having one of its ends extending out side of the combustion-chamber proper and secured to a shaft journaled exteriorly of the

said cylinder, a clamping-block secured to the said shaft, a spring-lever secured to the said clamping-block, a cam mounted upon a working part of the engine and adapted to strike the said spring-lever whereby the oscillating electrode is adapted to be actuated with a snapping movement and a spring secured to the clamping-block and adapted to engage the exterior wall of the combustion-chamber for holding the oscillating electrode normally away from the stationary electrode, substantially as described.

7. In an explosive gas or gasoline engine the combination with a cylinder and combustion-chamber, inlet and exhaust valves, a pivoted lever for actuating said valves alternately, a cam engaging said lever directly for operating the same, sparking devices in the combustion-chamber, an auxiliary inlet-valve governing the supply of hydrocarbon, a bell-crank lever entirely independent of the valve-actuating lever pivotally mounted upon said engine for controlling the supply and consequently the speed of the engine and a governor connected to the engine and said bell-crank lever for operating the latter, substantially as described.

8. In an explosive gas or gasoline engine the combination with a cylinder and piston, of valves covering respectively an inlet and an exhaust from said cylinder, a closed cam connected to the moving parts of the engine, and a pivoted lever engaging said cam, whereby the same is adapted to positively open the valves alternately, substantially as described.

In testimony whereof I hereunto affix my signature in presence of two witnesses.
